US0D1011706S

(12) United States Design Patent (10) Patent No.: US D1,011,706 S
(45) Date of Patent: * Jan. 23, 2024

(54) HIGH HEEL

(71) Applicant: Lingli Wang, Chengdu (CN)

(72) Inventor: Lingli Wang, Chengdu (CN)

() Term: 15 Years

(21) Appl. No.: 29/888,577

(22) Filed: Apr. 3, 2023

(51) LOC (14) Cl. 02-04

(52) U.S. Cl. D2/930
USPC D2/930

(58) Field of Classification Search

USPC D2/929, 930, 932, 946, 971, 972
CPC A43B 3/00; A43B 21/24; A43B 17/02;
A43B 3/122; A43B 3/12; A43B 3/0036;

A43B 9/14

(57) CLAIM

The ornamental design for a high heel, as shown and described.

DESCRIPTION

FIG. 1 is a top perspective view of a high heel showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the area identified as '9' in FIG. 1;

FIG. 10 is an enlarged view of the area identified as '10' in FIG. 2;

FIG. 11 is an enlarged view of the area identified as '11' in FIG. 2;

FIG. 12 is an enlarged view of the area identified as '12' in FIG. 8; and,

FIG. 13 is an enlarged view of the area identified as '13' in FIG. 8.

The broken lines in the figure views are used to identify areas of enlargement and form no part of the claimed design.

1 Claim, 9 Drawing Sheets
